ERNEST C. COX, OF NEWPORT NEWS, VIRGINIA.

TIME-LOCK.

1,198,895.

Specification of Letters Patent. Patented Sept. 19, 1916.

Application filed December 13, 1915. Serial No. 66,547.

To all whom it may concern:

Be it known that I, ERNEST C. Cox, a citizen of the United States, and a resident of Newport News, in the county of Warwick and State of Virginia, have invented a certain new and useful Improvement in Time-Locks, of which the following is a specification.

My invention relates to time locks, more especially to locks for automobiles, and it consists in the combinations, constructions, and arrangements herein described and claimed.

An object of my invention is to provide a time lock which will prevent the operation of an automobile by securing the steering rod so that the latter cannot be turned, and at the same time breaking the ignition circuit.

20 A further object of my invention is to provide a device of the type described in which an ordinary alarm clock is used for the time piece and is so arranged that at any given time it will automatically unlock the device and close the ignition circuit, thereby permitting the operation of the machine in the normal way.

30 A further object of my invention is to provide a device of the type described having means whereby the owner or operator of the automobile may unlock the device at any time.

35 A further object of my invention is to provide a device of the type described, which is exceedingly simple in construction, easy to manufacture, and not liable to get out of order.

40 Other objects and advantages will appear in the following specification, and the novel features of the invention will be particularly pointed out in the appended claims.

My invention is illustrated in the drawing accompanying the application, and in which—

45 Figure 1 shows the application of the device to an automobile. Fig. 2 is a sectional view through the device. Fig. 3 is a bottom plan view, the hinged bottom being removed, and certain parts being shown in section. Fig. 4 is a sectional view along the line 4—4 of Fig. 2, showing a portion of the clock. Fig. 5 is a similar view showing the parts in a different position. Fig. 6 is a perspective view of a portion of the actuating mechanism of the clock. Fig. 7 is a perspective view showing a portion of the locking mech-

anism. Fig. 8 is a perspective view showing the hinged bottom or door.

In carrying out my invention I provide a casing 1 of oblong shape as shown in the drawing. This casing may be of any suitable material, but is preferably made of metal and is provided with an extension 2, the latter being in the form of a sleeve arranged to fit over the steering post 3 as shown in Figs. 2 and 3, and to be secured in position upon said post by means of a set screw 4, or other suitable holding device.

The casing 1 is provided with a hinged bottom 5 which is attached to the casing at 6, and which is provided with the locking members 7 arranged to enter registering openings 8 in the lock casing 9, said lock casing 9 being carried on the interior of the casing 1. The lock of which the casing 9 forms a part, may be of any suitable shape or form. In the present instance I have illustrated generally a combination lock, having a knob 10 by means of which the lock may be set to open, but it will be understood that any form of lock might be used without departing from the spirit and scope of the invention.

Extending transversely of the casing are supporting members 11 and 12, these supporting members being provided with openings 11^a and 12^a respectively, through which the bolt 13 of the lock is arranged to slide. As will be observed from Fig. 7, the bolt is provided with shoulders 13^x and 13^y. When the latch bolt is in its locking position as shown in Fig. 2, a spring 14 which is secured to the support 11, engages the shoulder 13^x, thereby preventing the retraction of the bolt. The spring may be released by the clock in the manner hereinafter shown.

In order to cause the forward movement of the bolt into its locking position, I have provided a slidable plate 15 having a projecting portion or arm 16 arranged to engage the shoulder 13^y of the bolt. The plate is held in a normally retracted position by means of a spring 17, but may be pushed forwardly so as to force the bolt into its locking position by means of a thumb piece 18 which projects through a slot in the door 5. A spiral spring 19 is disposed between the support 11 and the collar 20 on the inner end of the bolt 13. This tends to normally retract the bolt.

As will be seen from Figs. 2, 3, and 7, the retraction of the bolt brings the inner end

of the bolt into engagement with a spring contact 21, and pushes the latter into engagement with a spring contact 22. These spring contacts are designed to be connected up in the ignition circuit (not shown), so that as long as the bolt is retracted, the circuit is closed, while when it is in its locking position the circuit is open. The forward end of the bolt 13 is arranged to extend through registering openings in the casing 1, the steering post 3, and the steering rod 23, so that when the bolt is in the position shown in Figs. 2 and 3, the steering rod cannot be turned with respect to the steering post, while when the bolt is in its retracted position, as shown in Fig. 7, the steering rod is free to turn.

The means by which the bolt is released at any predetermined time, consists of an alarm clock which I have designated in general by C. In the drawings I have shown merely the parts that relate directly to the release mechanism. In Figs. 4 and 5, 24 denotes a shaft bearing a pointer 25 which may be turned to any position on the time dial (not shown). This shaft bears a collar 26 having a lug 26^x, see Fig. 6. Loosely mounted on the shaft 24 and slidable thereon, is a gear 27 whose hub 28 is provided with a recess 29, one edge of which is parallel with the axis of the shaft 24 and the other edge is beveled as shown in Fig. 6. A spring 30 is secured at one end to the frame of the clock and is provided with an opening through which the shaft 24 extends. The end of the spring is forked as shown at 32 and engages a grooved collar 33 on a rod 34 which extends at right angles to the spring, through the casing of the clock and into engagement with the spring 14. The gear 27 may be driven in any suitable manner from the winding stem of the alarm mechanism, this winding stem being shown at 35 in Fig. 6. In the present instance I have shown the train as consisting of the gears 36, 37, 38, and 27, but it will be obvious that any other suitable arrangement might be used.

From the foregoing description of the various parts of the device, the operation thereof may be readily understood.

The device is designed to be used to prevent the theft or unlawful use of automobiles, as stated. Many times chauffeurs will use machines which are supposed to be in garages, without the consent of the owner. The device is secured to the steering post in the manner described and the time piece may be set for releasing the mechanism at any predetermined time, say at 7 o'clock a. m. The stem 24 is turned in the usual manner to set the release mechanism, which corresponds to the alarm mechanism, thereby bringing the parts into the position shown in Fig. 4. It will be noted that the shaft 24

projects rearwardly from the clockwork, that is to say, away from the face of the clock but into such position that it may be readily reached when the door 5 is open. A shaft 24^w also projects rearwardly and is used to wind the clock. The bolt is pushed forward into locking position by means of the thumb piece 18 and the spring 14 will engage the shoulder 13^x so as to retain the bolt in this position, this spring 14 being held by the rod 34. It will now be impossible to turn the steering wheel, since the steering rod is in locked condition. Furthermore the ignition circuit is disconnected as already described, by the separation of the contacts 21 and 22. When the hour of 7 arrives, the shaft 35 will revolve in the reverse direction, as in the case of the ordinary alarm clock. This will cause the rotation of the collar 28 through the medium of the gear train until the recess 29 comes into registration with the lug 26^x, whereupon the spring 30 will press the gear 27 and its collar into the position shown in Fig. 5. The movement of the spring will shift the rod 34, thus relieving the tension on the spring 14 and permitting the latter to withdraw from the shoulder 13^x, by its own resiliency whereupon the spring 19 will retract the bolt.

It is obvious that at certain times the owner of the machine may want to use it after the time lock has been set, and to this end I have provided the lock which permits the opening of the bottom of the casing, giving access to its interior. As stated before, this is shown to be a combination lock, but may be of any suitable nature. When the door is unlocked, the bolt 13 may be retracted by lifting the spring 14 from the shoulder 13^x.

I claim:—

1. In a time lock for automobiles and the like, a casing, a spring pressed locking bolt carried within the casing, means for retaining the bolt in its locking position, said means comprising a spring arranged to engage a portion of the bolt, a slidable rod for holding the spring in operative relation with the bolt against the tension of the spring, a second spring arranged to exert tension on the rod to withdraw the rod from the first mentioned spring, and means for permitting the movement of the second named spring at a predetermined time.

2. In a time lock for automobiles and the like, a casing, a spring pressed lock bolt slidably disposed within the casing and provided with a shoulder, a spring having one end arranged to engage behind the shoulder, a slidable rod having one end in engagement with said spring to retain the latter in its locking position, said rod having a groove at one end, a spring having a forked portion arranged to enter the groove, said second

named spring tending to force the rod away from the first named spring, a slideable gear arranged to bear on said second named spring for normally retaining the latter in its initial position, and means for releasing the gear to permit the movement of said second named spring.

3. In a time lock for automobiles and the like, a casing, a spring pressed bolt carried by the casing, said bolt being provided with a shoulder, a leaf spring having one end normally in engagement with the shoulder of the bolt for holding the same in locking position, a slideable rod for holding the leaf spring in engagement with the bolt, a second spring for exerting tension on the rod in the opposite direction to release the leaf spring, a gear provided with a hub having a recess, a shaft passing through the center of the gear and bearing a lug arranged to enter the recess in the hub.

4. In a time lock for automobiles and the like, a casing, a spring pressed locking bolt

carried thereby and provided with a shoulder, a spring having one end adapted to engage said shoulder for retaining the bolt in its locking position, a slideable rod normally in engagement with said spring, a second spring for exerting tension on the rod to hold it in engagement with the first named spring, a shaft rotatable to any desired position, a lug carried by the shaft, a gear mounted for revolution on the shaft, a hub secured to said gear and having a recess on one side thereof, arranged to receive the lug when the lug is brought into registration with the recess, said gear being engaged by said second named spring, and the movement of the gear along the shaft serving to permit the movement of said second named spring and the withdrawal of the rod from the first named spring.
